UNITED STATES PATENT OFFICE.

CHARLES B. GILLESPIE, OF GRAND FORKS, NORTH DAKOTA.

MEANS FOR EXCLUDING FLIES FROM BUILDINGS.

1,005,535.

Specification of Letters Patent.

Patented Oct. 10, 1911.

Application filed May 25, 1911. Serial No. 629,365.

To all whom it may concern:

Be it known that I, CHARLES B. GILLESPIE, a citizen of the United States of America, and a resident of Grand Forks, 5 in the State of North Dakota, have invented a new and useful Improvement in Means for Excluding Flies from Buildings, of which the following is a specification.

10 This invention is primarily additional to the subject-matter of a companion specification of the same date and title; but the fly-proof wickets and exit doors to which the present specification is confined may be 15 employed in connection with fly-proof entrances differing in construction from those set forth in said companion specification.

The leading objects of the present invention are to prevent the entrance of flies into 20 a building or an apartment by way of wickets for the delivery of goods, or of the exit doorways.

Other objects will be set forth in the general description which follows.

25 Three sheets of drawings accompany this specification as parts thereof.

Figures 1 and 2 are perspective views of an oscillating wicket constructed according to this invention; Figs. 3 and 4 are horizontal sections of the same, showing its doors in the positions represented by Figs. 1 and 2 respectively; Figs. 5 and 6 are horizontal sections thereof showing the doors in other positions; Figs. 7 and 8 are detail 35 views of its latch on a larger scale; Figs. 9 and 10 are large-scale detail views showing respectively the spring hinge and telescopic construction of its secondary door; Figs. 11 and 12 are plan views of a revolving 40 exit door for persons, constructed on the same principle.

Like reference characters refer to like parts in all the figures.

The wicket *a* and exit *b*, which together 45 constitute the means of the present invention for excluding flies from buildings or apartments, are constructed; in common, with a vertical axis of motion; and with radial main doors, 1 and 2, or 1' 2' 3' and 50 4' rigidly united by a pivot post, 5, forming sector-shaped passageway spaces between

them, and turning within a suitable housing formed in part by a segmental wall, 6 or 6'; together with secondary swinging doors, 7 or 7', between the main doors. The secondary doors, 7 or 7', are also, in common, provided with peculiarly operated latches, 8, hereinafter more particularly described, one of which is shown in detail by Figs. 7 and 8, and with spring hinges, one of which is represented at 9 in Fig. 9, by which each secondary door 7 or 7' is normally held against the back of the main door to which it belongs, and is restored to this position after being temporarily detained in its fly-excluding position, while the main door moves away therefrom; the unlatching contact of a main door with the secondary door being adapted to kill any flies that may be between the two. Said latches 8, common to both devices, are of the following construction: (See Figs. 7 and 8.) A housing, 10, adapted to be fixedly attached to the secondary door 7 or 7' and suitably recessed, guides a horizontally slideable bolt, 11, the protruding end of which is or may be beveled, and which is provided with a longitudinal spur rack, 12, engaged by a pinion or sector, 13, forming the hub of a lever arm 14. A coiled spring, 15, keeps the bolt 11 normally protruded; and the lever arm 14 and rack and pinion connection are retracting means. The spring hinges 9, Fig. 9, may be of any suitable known or improved construction; as may also said latches 8; neither of them forming any part of the present invention, as regards their details of construction.

The housing of the wicket *a*, Figs. 1 to 6, inclusive, shown at 6, is adapted to be supported upon a sales counter, *c*, Figs. 1 and 2, in juxtaposition to an opening fitted thereto and formed in a vestibule wall, *d*, or the like, which is further provided with a conveniently located cash slot, *e*, as represented in the same figures. The housing is sector-shaped and open at both radial sides thereof; it includes horizontal top and bottom members, 16 and 17, in addition to its segmental wall 6; and its pivot post 5 has bearings in said top and bottom members. Its inner and outer main doors 1 and 2 are

provided respectively with a handle, 18, and with a latch-retracting projection, 19, adjoining which a recess 20 admits more or less of the latch as required. Its latch 8 is carried by the opposing side or back of its secondary door 7, which is pivoted with the aid of one or more of said spring hinges 9 close against the post 5. To compensate for the difference in length of radius between the main doors 1 and 2 and the secondary door 7, the latter is constructed with a telescopic free edge, 21, shown in detail by Fig. 10; which see. The outer edge portion (21) is projected by the customary springs 22, and its projection is limited by stops 23. The overlapping portions may preferably be made of thin sheet metal so as to be substantially flush.

The main doors 1 and 2 are connected at their lower edges by a bottom, 24, on which parcels are placed by the salesman after pulling the wicket by the handle 18 from its position of rest, Figs. 1 and 3, into the receiving position represented by Fig. 5; the secondary door 7 being in contact with the back of the inner door 1, and the entrance of flies prevented by the outer door 2 within the housing. The wicket is then moved by the salesman to its delivering position, Figs. 2 and 4, and the parcels are removed by the purchaser. The outward movement of the wicket is continued until it is arrested by a stop, 25. At the same instant a catch recess, 26, admits the bolt 11 of the latch 8 as in Fig. 4, and the secondary door 7 becomes fastened in the outer opening of the wicket housing, so as to exclude flies therefrom during the return movement of the emptied wicket, as represented by Fig. 6. Toward the end of this movement, the projection 19 of the outer door 2 comes in contact with the lever arm 14 of the latch 8, and retracts the latch bolt 11; permitting the secondary door 7 to be thrown into contact with the back of the inner main door 1 by its spring hinge 9. The movement of the wicket from this position (Figs. 1 and 3) to its receiving position (Fig. 5) is limited by the wall *d* through which the passageway of the wicket extends.

The housing of the fly-proof exit *b*, Figs. 11 and 12, in addition to its segmental wall 6', has a nearly circular top, 27, Fig. 12, and diametrically opposite said segmental wall has a segmental guard, 28, which may preferably be a railing or grille, as indicated, and of larger radius than the segmental wall, so as to obviate making the secondary doors 7 telescopic. These secondary doors are or may be otherwise of the same construction, excepting dimensions, as the secondary door 7 above described; having in common therewith latches 8 and spring hinges 9 as already described. For tripping

the latches 8, each of the main doors 1' 2' 3' 5' and 4' is likewise constructed with a retracting projection 19 and a recess 20 adjoining the same similar to those above described. In this device the main doors 1' 2' 3' and 4' are adapted to be revolved continuously by persons leaving the fly-proof apartment from which the exit passageway leads; the latches 8 interacting successively with a striking plate, 30, attached to a post, 31, at the outer end of the segmental guard 28. 75

With the doors 1' 2' 3' 4' and 7' in the positions represented by Fig. 11, the main door 1' has just released one of the secondary doors 7' from the post 31, and is about to leave in its place the secondary door 7' 80 normally carried on the back of said main door 1'. In this condition of the exit, both of the outer doorways, 32 and 33, of the exit are closed by the main doors 2' and 1' respectively, and persons may be supposed to be between the doors 2' and 3' and between the doors 3' and 4' and pressing against the backs of said doors 2' and 3' respectively as represented by the arrows *x* and *y*. An instant later the parts would appear as shown 90 in Fig. 12; the person or persons represented by said arrow *x* leaving the exit, and the space between the doors 4' and 1' opening for the reception of a person or persons, represented by the arrow *z*. As here shown, 95 the doorway 32 is open, but the passageway leading therethrough is effectively obstructed by the door 3' interacting with the fly-proof segmental wall 6', and the doorway 33 is closed by the secondary door 7' left by the main door 1'. When the main door 2' reaches this secondary door 7' the projection 19 of the main door trips the latch 8 of the secondary door, and the latter is thrown by its spring hinge 9 into its normal position again, in contact with the back of the main door 1'; the next secondary door, normally in contact with said door 2', taking its place as the obstruction of the doorway 33 against the entrance of flies. The entrance of persons between a main door and its secondary door is prevented by the guard 28; and as the doorway 33 adjoining the same is always closed, either as shown in Fig. 11 or as shown in Fig. 12, said guard need not be fly-proof.

The exit *b* represented by the drawings is one of a pair made "right" and "left" respectively and arranged at the respective inner angles of the rectangular inner end of a vestibule, in connection with a separate fly-proof entrance, as set forth in said companion specification.

For the purposes of the present invention the fly-proof entrance or entrances may be of any known or improved construction.

Certain modifications in matters of detail have been mentioned; and other like modifi-

cations will suggest themselves to those skilled in the art.

Having thus described said improvement, I claim as my invention, and desire to patent under this specification:

1. In means for excluding flies from a building, the combination of radial main doors rigidly connected with each other and forming a passageway space between them, a secondary door arranged within said space and normally in contact with one of said main doors, means for temporarily detaining said secondary door in its fly-excluding position while the main door last mentioned moves away therefrom, and means for restoring said secondary door to its normal position with reference to this main door.
2. In means for excluding flies from a building, the combination with radial main doors rigidly connected with each other and forming a passageway spaced between them, of a secondary door arranged within said space and normally in contact with one of said main doors, a latch carried by said secondary door for temporarily detaining it in its fly-excluding position, while the main door last mentioned moves away therefrom, a relatively fixed part adapted to interact with said latch, means for unlatching said latch, and means for restoring said secondary door to its normal position with reference to said last mentioned main door.
3. In means for excluding flies from a building, the combination with a vertical pivot post of main doors projecting rigidly therefrom and forming a passageway space between them, a secondary door, arranged within said space, having vertical hinges adjoining said post including a spring hinge adapted to keep it normally in contact with one of said main doors, means for temporarily detaining said secondary door in its fly-excluding position while the main door last-mentioned moves away therefrom, and means for releasing said secondary door and permitting it to resume its normal position with reference to this main door.
4. In means for excluding flies from a building, the combination with a housing having a segmental wall of main doors having the same radii rigidly connected with each other forming a sector-shaped passageway space between them, a secondary swinging door movable within said space and normally in contact with one of said main doors, means for temporarily detaining said secondary door in its fly-excluding position while the main door last mentioned moves away therefrom, and means for restoring said secondary door to its normal position with reference to this main door.
5. In means for excluding flies from a building, a fly-proof wicket for goods, having, in combination, a fixed sector-shaped
- housing open at both radial sides thereof, a pair of main doors pivotally movable within and through the same rigidly united with each other and forming a passageway space between them, a bottom movable with said main doors and adapted to carry the goods, a secondary swinging door movable between said main doors and normally in contact with one of them, a handle attached to this main door, means for detaining said secondary door in its fly-excluding position during the retraction of said main doors and bottom, and means for restoring said secondary door to its position in contact with the handle carrying main door.
6. In means for excluding flies from a building, a fly-proof wicket for goods, having, in combination, a fixed sector-shaped housing open at both radial sides thereof, inner and outer main doors pivotally movable within and through the same, rigidly united with each other and forming a passageway space between them, a bottom movable with said main doors and adapted to carry the goods, a secondary swinging door movable between said main doors and normally in contact with the inner door, a handle attached to this inner door, a latch having a lever-arm retracting device and adapted to hold said secondary door in its fly-excluding position during the retraction of said main doors and bottom, and means for restoring said secondary door to contact with said inner door including a projection carried by said outer door on its back in juxtaposition to said lever arm.
7. In means for excluding flies from a building, a fly-proof wicket for goods having, in combination, a fixed sector-shaped housing open at both radial sides thereof, inner and outer main doors pivotally movable therethrough and forming a sector shaped space between them, a vertical pivot post and a horizontal bottom rigidly connecting said doors, a secondary swinging door normally in contact with the back of said inner door within said space, having a hinge edge adjoining said post, means for detaining said secondary door in its fly-excluding position during the retraction of said main doors and bottom, and means for restoring said secondary door to its position in contact with said inner main door, including a spring hinge at said hinge edge.
8. In means for excluding flies from a building, a fly-proof wicket for goods having, in combination, a fixed sector-shaped housing open at both radial sides thereof, inner and outer main doors pivotally movable therethrough and forming a sector-shaped space between them, a vertical pivot post and a horizontal bottom rigidly connecting said doors, a secondary swinging door normally in contact with the back of

4
said inner door within said space; having a hinge edge adjoining said post and made telescopic to compensate for the differences in length of radii, means for detaining said secondary door in its fly-excluding position during the retraction of said main doors and bottom, and means for restoring the telescopic secondary door to its position in contact with said inner main door, substantially as hereinbefore specified.

CHARLES B. GILLESPIE.
